United States Patent Office.

JAMES H. HALL, OF MAYSVILLE, KENTUCKY.

Letters Patent No. 75,414, dated March 10, 1868.

IMPROVEMENT IN THE MODE OF ATTACHING COULTERS TO PLOUGH-BEAMS.

The Schedule referred to in these Letters Patent and making part of the same.

TO ALL WHOM IT MAY CONCERN:

Be it known that I, JAMES H. HALL, of the city of Maysville, county of Mason, and State of Kentucky, have invented a new and useful Wrought-Iron Sliding Plate, by which to regulate and hold fast the Cutter to a Plough-Beam; and I do hereby declare that the following is a full and exact description, reference being had to the accompanying drawings, and to the letters of reference thereon.

The nature of my invention consists of a wrought-iron plate with an upper flange, *a*, in front of the cutter *b*, and a lower flange, *c*, behind the cutter, with mortises *d d*, to slide the plate forward or backward, as the cutter may be needed to be moved forward or backward. The plate is attached to the plough-beam by means of the bolts *e e*, and the cutter held between the flanges by the band *f*. The plates upon the upper and lower parts of the beam form a groove in which the sliding plate moves.

What I claim as my invention, and desire to secure by Letters Patent, is—

The said wrought-iron sliding plate, with its flanges, mortises, and adaptation to the purpose of regulating the position of and holding fast the cutter to a plough-beam.
